UNITED STATES PATENT OFFICE

EVAN E. WYATT, OF LOS ANGELES, CALIFORNIA

INSTRUCTION DESK ASSEMBLY

Application filed March 4, 1931. Serial No. 519,959.

My invention relates to an instruction desk assembly and has for its principal object, the provision of a relatively simple, practical and compact desk assembly that may be advantageously utilized in educational and industrial institutions or wherever desired for the accommodation of an instructor and a number of students or persons who are to receive collective or individual instruction.

Further objects of my invention are, to provide an instruction desk assembly that is strong and durable in construction, very compact so that it occupies comparatively little floor space and arranged so that all students and all persons receiving instruction face the teacher or instructor, further, to provide an instruction desk assembly having conveniently located and arranged compartments for the accommodation of the books, writing materials and other instruction paraphernalia and requisites, further, to provide a desk assembly having closed storage spaces for articles of wearing apparel and other personal belongings of the students or persons receiving instruction and further, to provide an instruction desk assembly of the character referred to that affords comfort and convenience to both teacher or instructor and to the persons or students receiving instruction.

With the foregoing and other objects in view, my invention consists in certain novel features of construction and arrangement of parts that will hereinafter be more fully described and claimed and illustrated in the accompanying drawings in which:

Fig. 1 is a top plan view of an instruction desk assembly embodying the principles of my invention.

Fig. 2 is a side elevational view of the instruction desk assembly.

Fig. 3 is an enlarged front and elevational view of the assembly.

Fig. 4 is a vertical cross section taken on the line 4—4 of Fig. 1.

Referring by numerals to the accompanying drawings which illustrate a practical embodiment of my invention, 10 designates a base frame preferably formed of metal straps that is substantially rectangular in form and

at the front end of the assembly the central portion of the transverse member 10^a of the base frame is extended forwardly to a central point so as to receive and support the base of a post 11 and swiveled on the top of said post is a seat 12 that is adapted to be occupied by the teacher or instructor.

Secured to the forward portions of the side rails of base 10 are posts 12^a, preferably of metal and these posts support a transversely disposed box-like structure 13 in the center of which is formed a compartment 14 and the top of this compartment is normally closed by a hinged cover 15.

This compartment 14 is positioned directly in front of the instructor's seat 12 and is adapted to contain paraphernalia and personal effects of the instructor and when the cover 15 is in closed position it provides a flat surface that performs the functions of a desk top.

Formed in the structure 13, immediately to the left of compartment 14 is a compartment 16, the top of which is closed by a hinged plate 17, preferably of metal, and this compartment is adapted to receive books and paraphernalia utilized by the instructor and a student when the latter is given personal instruction.

The cover 17, when closed, performs the functions of a desk top.

Mounted for swinging movement upon the lefthand one of the front posts 12^a, is a horizontally disposed arm 18 and swiveled upon the free end of said arm is a seat 19 that is adapted to be occupied by the student or person receiving individual instruction. When occupied by a student this seat 19 is positioned immediately to the left of the instructor's seat 12 and said seat 19 is swiveled and mounted on the swinging arm 18 so as to enable the student or person receiving instruction to conveniently occupy said seat or to arise and leave the same after receiving individual instruction.

Depending from the right hand portion of the structure 13 is a housing or frame work 20 and arranged for sliding movement therein and disposed one above the other, is a series of drawers 21 for the accommodation of

papers, books and other adjuncts utilized by the instructor and the students or persons receiving instruction.

The top of this side structure occupies the 5 same horizontal plane with the hinged plate or cover 15, thus combining with the latter to function as a desk top and formed in the rear portion of this top are recesses 23, for the accommodation of pens, pencils, ink and 10 like writing materials.

Arranged above the base 10, to the rear of the front structures 13 and 20, are transversely disposed desk structures that are used by the students or persons receiving instruction 15 and arranged immediately to the rear of each desk structure are seats for the students or persons receiving instruction.

In the drawings, I have illustrated three double desks to be utilized by the students 20 and six seats for the students or persons receiving instruction, but as the construction of these desks and seats are identical, it will only be necessary to describe one desk and the 25 seats that are associated therewith. Obviously the number of students' desks and seats may be increased or diminished from the number herein shown and described.

Each student's desk comprises a horizontally disposed substantially rectangular housing 24, preferably formed of sheet metal or 30 wood veneer and the space within each housing is divided so as to form a pair of compartments 25 that are adapted to receive books, writing material and personal effects 35 of the students or persons receiving instruction.

Arranged in the upper portion of each compartment is a horizontally disposed partition 26 and the relatively narrow space 27 above 40 each partition is adapted to receive large forms, record sheets and the like that are used by the students or persons receiving instruction and which are not to be folded.

In order to facilitate the removal of these 45 relatively large sheets each partition 26 is provided with a longitudinally disposed slot 28 that extends rearwardly from the front edge of the partition, thus enabling the thumb and index finger to readily grasp the edges 50 of sheets lying on the partitions.

The top of each compartment 27 is closed by a plate or panel 29, preferably formed of sheet metal and which is connected by suitable hinges 30 to the rear transverse member 55 of the structure 24. The plates or panels 29 when closed provide flat surfaces that function as desk tops.

Arranged between each pair of hinged top plates or panels 29, is a longitudinally disposed plate 31 that is fixed to the upper portion 60 of the housing or structure 24 and formed in this plate are depressions 32 that are adapted to receive pens, pencils, ink and similar writing materials.

Depending from the intermediate portion

of each housing 24 and beneath the rear portion thereof, is a substantially rectangular structure 33, preferably formed of sheet metal and arranged within this structure is a vertically disposed partition 34 that divides 70 the space into two narrow vertical compartments or storage spaces 35.

Arranged within the upper portion of each compartment 35, is a horizontally disposed partition 36, thus providing in the upper portion of each housing 33, a pair of relatively small compartments or storage spaces 37 which may receive books, papers and personal effects of the students or persons receiving 75 instruction.

The compartments 35 and 37 are closed at their forward ends by doors 38 that are hinged to the front central portion of the structure 33.

The small triangular plates that appear in front of the upper inner corners of the doors 38 in Fig. 4, are arranged a sufficient distance in front of the structure 33 and said doors to permit the latter to swing into full open 80 positions.

Secured to transversely disposed base members 10^b and projecting upwardly to the rear of each desk structure 24 are pairs of upright members 39 and the upper ends of each of these pairs of members are connected by 85 transversely arranged curved rail 40. These upright members and curved rail constitute seat frames and the upper portion of each frame is suitably connected by brackets such as 41 to the front edge of the desk structure 90 24 that is disposed immediately to the rear of the seat frames.

Pivotedly arranged between the lower portions of each pair of uprights 39 are seats 42 that are adapted to be occupied by the students or persons receiving instruction and arranged beneath each seat is a hat supporting 95 rack or hanger 43.

It will be understood that there is one seat frame and seat as just described, arranged immediate to the rear of each desk compartment 25 and its hinged cover 29.

Rigidly secured to the underside of each desk structure 24 and located in the same vertical plane with the partitions 34, are longitudinally disposed frames 44, each frame carrying a section of wire netting 45 and these frames function as partitions as well as longitudinally disposed reinforcing members for 110 the entire structure.

Extending from the front ends of these frames to the rear ends of the next adjacent frames and disposed midway between each pair of seats 43 and seat frames 39, are frames 46 that carry sections 47 of wire netting and which also perform the function of partitions and centrally arranged strengthening members.

The frames 44 and 46 are rigidly fixed to 115 each other and to the housings 24.

Secured in any suitable manner to transverse base member 10^b and disposed beneath each seat 42, is an open-topped box 48, that may be used as a storage space for overcoats, 5 raincoats and overshoes belonging to the students or persons receiving instruction.

At the rear end of the desk assembly the rear pair of seat frames 39 are secured to an upright frame 49 that projects upwardly 10 from the rear portion of base frame 10.

Thus it will be seen that my improved instruction desk assembly provides separate seats and desks for each student or person receiving instruction and that said assembly 15 also includes storage spaces and compartments for the paraphernalia utilized by the students as well as compartments or storage spaces for the hats and articles of wearing apparel belonging to the students.

20 The seating arrangement of the assembly is such that the students or persons receiving instructions all face the instructor and the seat 19, positioned adjacent to the instructor's seat enables a student to occupy a position to 25 the side of the instructor while receiving individual instructions. The entire instruction desk assembly is very compact, requires comparatively little floor space and is very effective in performing the functions for which it 30 is intended.

It will be understood that minor changes in the size, form and construction of the various parts of my improved instruction desk assembly may be made and substituted for 25 those herein shown and described without departing from the spirit of my invention, the scope of which is set forth in the appended claims.

I claim as my invention:

40 1. In an instruction desk assembly, a base, a plurality of transversely disposed desk structures supported in spaced relation upon said base, seat supporting frames projecting upwardly from the base to the rear of said desk 45 structures, a pair of folding seats hinged to each seat supporting frame, an instructor's desk structure mounted upon the front end of said base, a post projecting upwardly from the base in front of the instructor's desk 50 structure, a seat swiveled on said post, a post supporting one corner of the instructor's desk structure, an arm mounted for swinging movement on said post and a seat carried by 55 said swinging arm.

55 2. An instruction desk assembly, as set forth in claim 1, with a pair of vertically disposed storage structures arranged beneath the central portion of each transversely disposed desk structure and longitudinally disposed partitions secured on the underside of each transversely disposed desk structure and extending between the members of each pair 60 of seats.

65 3. In an instruction desk assembly, a base, a plurality of transversely disposed desk struc-

tures supported upon said base, said desk structures being spaced apart longitudinally of said base, each desk structure having two compartments, a cover hinged to the desk structure for each compartment, a seat supporting frame projecting upwardly from the base to the rear of each desk structure, a pair of seats supported by said seat supporting frame and arranged side by side, an instructor's desk supported on the front portion of 70 said base, a post projecting upwardly from the base in front of the instructor's desk structure, a seat swiveled on said post, a post supporting one corner of the instructor's desk structure, an arm mounted for swinging movement on said post and a seat carried by 75 said swinging arm.

4. An instruction desk assembly as set forth in claim 3, with containers secured to and depending from the intermediate portions of said transversely disposed desk structures and longitudinally disposed partitions secured to the undersides of said desk structures and arranged between the upper 80 portions of said containers and extending between the seats located to the rear of said transversely disposed desk structures.

In testimony whereof I affix my signature.
EVAN E. WYATT.
